UNITED STATES PATENT OFFICE.

HARRY P. MARTIN, OF CLEARFIELD, PENNSYLVANIA.

ROAD-CONSTRUCTION MACHINERY.

1,384,077.

Specification of Letters Patent. Patented July 12, 1921.

Application filed April 23, 1921. Serial No. 463,912.

To all whom it may concern:

Be it known that I, HARRY P. MARTIN, a citizen of the United States, and a resident of Clearfield, county of Clearfield, and State 5 of Pennsylvania, have invented an Improvement in Road-Construction Machinery, of which the following is a specification.

This invention relates to road construction machinery and more particularly to 10 machinery adapted to the distributing of road-making material over the roadbed.

One of the objects of the invention is to provide practical and reliable means that will operate regardless of the slope or character 15 of the ground upon which it is set up.

Another object is to provide a simple and effective means, readily movable from place to place, whereby trucks and the like may be mounted thereon and revolved into any 20 position desirable on the roadbed before dumping the material; to also offer an effective means of distributing the contents of the truck or the like, by dumping the same while the truck is being bodily rotated.

25 Another object of this invention is to provide a turntable that is rugged in structure, easily manufactured from readily obtainable material of a commercial section, and adaptable in every respect to concrete road 30 construction.

In the construction of pavements, concrete roads, and the like, it is necessary to set forms for the retaining of concrete and other material. Since standard State highway 35 roads are generally eighteen feet or less in width, it is impossible to turn a truck or the like without damaging the forms set to limit the width of the concrete roadbed. Furthermore, such an attempt to turn or position 40 a truck, which is usually about fourteen feet in length, would result in a blocking of the passage and of forcing other trucks to lie idle during this period. This of course limits the speed of construction and 45 hinders progress in many other respects. It is therefore desirable to bodily rotate the trucks into position for the pouring of concrete and other materials. The ordinary structures obtainable for this work, while 50 they may be able to position the trucks, are so large that they obstruct permanently the passageway between the molds and are accordingly detrimental as hereinbefore pointed out.

55 This invention, among other objects, aims

to provide a simple, rugged structure that will quickly and effectively position the truck as desired and one that will only obstruct the passageway temporarily while the truck is in a position perpendicular to the 60 sides of the road. This, of course, greatly facilitates the handling and hauling of the material, and as a result a maximum amount of work at a maximum speed is possible.

In the accompanying drawings, in which 65 is shown one embodiment of this invention by way of example and in which similar reference characters refer to similar parts thereof,

Figure 1 is a top plan view, the dotted 70 position being that assumed by the structure when the truck is to be turned perpendicular to the roadbed;

Fig. 2 is a side elevation of Fig. 1;

Fig. 3 is a detailed drawing of a portion 75 of Fig. 1, showing the method of construction;

Fig. 4 is a side elevation of Fig. 3, showing one of the supporting wheels of the structure and also a wheel of a truck 80 mounted thereon; and

Fig. 5 is a cross-section of Fig. 3 on the line 5—5.

Referring to the drawings of the illustrated embodiment and more particularly to 85 Fig. 1, the numeral 10 designates the main body members which are rigidly fixed together by the transverse members 11 to form the rotatable part of the structure. Upon these main body members, which are preferably made from ordinary channel beams, the loaded trucks may be rolled from either end thereof. When the truck has reached substantially the center of the table it is stopped 90 and the table is rotated on the main thrust bearing, which will be more fully described hereinafter, the wheels operating on the track 12 aiding in the operation when necessary. The power for this purpose may be supplied by a few men, or in any other convenient manner. It will be seen that the entire structure is readily laid between the molds 13, which limit the width of the roadbed, and that the structure ordinarily occupies but one-half of the road or passageway. 95 It does temporarily occupy the entire passageway when it is desired to turn the structure perpendicular to the roadbed, as is shown in the dotted position of Fig. 1, but since it remains in this position only mo- 100 105 110

mentarily, the obstruction is of insufficient duration to be a material detriment to the progress of the work.

Referring again to the drawings, it will be seen that the ends of the transverse members 11 are securely and rigidly fastened to the main body members 10 by means of the angle irons 20 and the rivets 21. Mounted upon the main body members 10 are the wheel chairs 15 in which the wheels 16 are fixed in any suitable manner, as by inserting their axles through the apertures 17 provided therefor. These chairs are preferably fixed to the main body members by means of the bolts 42 inserted through the apertures 18. The track 12, upon which these wheels operate, is preferably made in four sections of any suitable material and is secured by bolts inserted through the apertures 19 to any suitable framework 45. Such a framework may be constructed by rigidly fastening the boards 44 to a pair of skids or runners 43, adding suitable braces if necessary, without exceeding a height of 3 inches. The main base member 23 is mounted on the framework 45 at substantially the center of the track. The skids or runners 43, in addition to providing a rigid framework, facilitate the removal of the structure from place to place along the roadbed as the work progresses.

The transverse members 14, whose ends are rigidly fastened to the main body members by the rivets 22, in addition to bracing the members 11 and making a rigid table out of the main body members, have another function which will now be more fully described. Referring particularly to Fig. 5, it will be seen that the members 14 are bent into substantially an arched shape to accommodate the thrust bearing 41. This arch is formed in any convenient manner, as by bending the above members at the four points 28, 29, 30 and 31, forming the straight portions 32, 32', 33, 33' and 34. Part 34 is of sufficient length to accommodate the pivoting part 27 of the main thrust bearing. The beams are bent downward at the points 29 and 30 and upward at 28 and 31, so that the extreme ends are substantially parallel to the member 34, but nearer to the ground. The arch thus formed must not be bent up in excess of the road clearance of the trucks to be carried. The main thrust bearing 41, constructed to have a low center of gravity, consists of the main supporting base member 23 and the pivoting member 27. The base member 23 has a concave spherical recess in its upper end. The pivoting member 27, which is rigidly fixed by means of the rivets 25 to the members 14, has its lower end in a convex spherical form, to coöperate with the concave recess in the upper end of the base member. These two members form a kind of ball and socket

joint which primarily centers, but in addition aids in the support of the table portion and permits the rotation thereof. It also allows slight movements perpendicular to the plane of rotation without causing any stresses in the bearing. This latter is found very desirable, especially when the load goes on or off the table. An aperture 40 is provided in the pivoting member for the admission of a lubricant, such as oil, to the surfaces 24 and 26 of the bearing.

It is usually impractical to make the channel members 10 sufficiently heavy to support the loads desired; for, in many instances, specially designed channel members would be required. In the present structure, standard channel beams are used and are reinforced by the members 36 and 36', which are rigidly secured to the main body members by means of the rivets 39. These reinforcing members may be of any suitable material and the dimensions will depend upon the size of the loads to be handled and its length will depend upon the length of the channels, which in turn will depend upon the length of the truck, generally about 14 feet.

Fig. 4 shows a wheel 37 of a vehicle mounted on one of the main channel members 10. It is readily seen that the flanges 35 and 35' and reinforcing members 36 and 36' prevent the wheels of the truck from sliding or running off the main channel members when the truck is once started on the table.

It is desirable that the main body members be as near the ground as possible, so that trucks may be mounted thereon with comparative ease. However, these members must be sufficiently high to clear the molds 13 when the structure is revolved in a position perpendicular to the roadbed. This height, of course, is determined by the height of the wheels 16 and the size of the thrust bearing and arch. It is desirable that the arch be sufficiently large to accommodate a comparatively large thrust bearing without causing the main body members to be unnecessarily high.

It will be seen that this entire structure is easily laid, since it is comparatively light and consists of a minimum number of parts and is likewise easily removed. No exact centering is required since the track is sufficiently wide to permit slight errors in the positioning thereof. It also effectively performs its function without obstructing permanently more than one-half of the roadway. It will be further noted that there is above provided in this invention a structure of simple and inexpensive construction and highly efficient action.

As various embodiments may be made in the invention above set forth and as many changes might be made in the structure here-

inbefore described, it is to be understood that all matter herein set forth is to be interpreted as illustrative and not in a limiting sense.

5. I claim as my invention:

1. In a device of the class described, in combination a track, wheels operating on said track, a pair of substantially parallel girders adapted to carry a load, means substantially centrally positioned with respect to said girders and secured thereto to pivot said girders for rotation and for carrying part of the load on said girders, means substantially co-axial with said pivoting means 10 and providing a supporting surface for said pivoting means and a plurality of arched transverse members coöperating with said girders and said pivoting means.

2. In a device of the class described, in combination a track, wheels operating on said track, a pair of substantially parallel girders adapted to carry a load, means substantially centrally positioned with respect to said girders to pivot said girders for rotation and for supporting part of the load on said girders, means substantially co-axial with said pivoting means and providing a supporting surface, a plurality of arched transverse members, coöperating with said 25 main body members and said pivoting means, and a plurality of transverse members to aid the said arched transverse members in holding the said girders in a definite position relative to each other.

3. In a device of the class described, in combination a track, wheels operating on said track, a pair of substantially parallel girders adapted to form a run-way for a truck mounted upon said wheels and an additional reinforcing member, coöperating with and rigidly fixed to each of said girders, a series of transverse members coöperating with said parallel girders to hold said girders in a fixed position, relative to each other and a central thrust bearing rigidly fixed to a plurality of said transverse members.

4. In a device of the class described, in combination, a track, wheels operating on said track, a pair of substantially parallel girders mounted upon said wheels, a series of transverse members coöperating with said girders to hold said girders in a fixed position relative to each other, a central thrust bearing composed of a main pivoting member and an additional base member co-erating therewith.

5. In a device of the class described, in combination, a track, wheels operating on said track, a pair of substantially parallel girders mounted on said wheels adapted to form a runway for the wheels of a truck, a series of transverse members coöperating with said girders to fix said girders substantially in a parallel position with respect

to each other, a supporting surface and a pivoting member coöperating with said supporting surface and rigidly fixed to a plurality of said transverse members.

6. In a device of the class described, in combination a track, wheels operating on said track, a pair of substantially parallel girders mounted on said wheels adapted to form a runway for the wheels of a truck, a series of transverse members coöperating with said girders to fix said girders substantially in a parallel position with respect to each other, a supporting surface and a pivoting member coöperating with said supporting surface and rigidly fixed to a plurality of said transverse members, said plurality of transverse members being arched to receive said supporting surface and pivoting member.

7. In a device of the class described, in combination a track, wheels operating on said track, a supporting surface and a pivoting member adapted to carry a load and to coöperate with said wheels to facilitate rotation, a pair of main body members adapted to form a runway for a truck and a reinforcing member rigidly fixed to each of said main body members for transmitting a part of the load on said members to the said pivoting member.

8. In a device of the class described, in combination a track, wheels operating on said track, pivoting load-carrying means coöperating with said wheels to facilitate rotation, a pair of main body members adapted to form a runway for a truck, and a reinforcing member rigidly fixed to each of said main body members for transmitting a part of the load on said members to the said pivoting load-carrying means.

9. In a device of the class described, in combination a track, wheels operating on said track, a centrally placed thrust bearing, a pair of main body members, and a plurality of substantially arched transverse members rigidly fixed thereto, said arched members being rigidly fixed to said thrust bearing and adapted to permit a relatively large thrust bearing without substantial raising of the two main body members.

10. In a device of the class described, in combination a track, wheels operating on said track, a centrally placed thrust bearing composed of a supporting surface and a pivoting member, a pair of body members adapted to form a runway for a truck and a plurality of substantially arched transverse members rigidly fixed to said pivoting member, said arched members being rigidly fixed to said thrust bearing and adapted to permit a relatively large thrust bearing without substantial raising of the two main body members.

11. In a device of the class described, in combination a track, wheels operating on

said track, a centrally placed thrust bearing, a pair of main body members adapted to receive a truck and a pair of substantially arched transverse members adapted to be fixed to the said central thrust bearing without substantial raising of the said main body members.

12. In a device of the class described, in combination a track, wheels operating on said track, a centrally placed thrust bearing composed of a main base member and a pivoting member, a pair of girders adapted to receive a truck and a pair of arched transverse members adapted to be fixed to said centrally placed thrust bearing without substantial raising of the said girders.

13. In a device of the class described, in combination a track, wheels operating on said track, a centrally placed thrust bearing composed of a main base member and a pivoting member, a pair of girders adapted to receive a truck and a pair of arched transverse members adapted to be fixed to said centrally placed thrust bearing, without substantial raising of the said girders, an additional pair of transverse members to aid said arched transverse members in fixing said girders substantially parallel to each other.

14. In a device of the class described, in combination a track, wheels operating on said track, a centrally placed thrust bearing, a pair of main body members adapted to form a runway for a truck, a pair of substantially arched transverse members adapted to be fixed to the said centrally placed thrust bearing without substantial raising of the said main body members, and a reinforcing member for each of said main body members and rigidly fixed thereto for transmitting a part of the load on said members to the said thrust bearing.

15. In a device of the class described, in combination a track, wheels operating on

said track, a centrally placed pivoting means, a pair of main body members adapted to receive a truck, means for transmitting a portion of the load on said main body members to the said pivoting members and a reinforcing member for each of said main body members and rigidly fixed thereto for distributing the load on said members to the said pivoting means.

16. In a device of the class described, in combination a track, wheels operating on said track, a pair of substantially parallel channel beams, a runway for a truck formed by the flanges of said beams, a reinforcing member rigidly fixed to each of said beams and forming an additional flange on each of said beams, a centrally placed thrust bearing adapted to carry part of the load on said channel beams and to facilitate rotation, a pair of substantially arched transverse members adapted to receive said centrally placed thrust bearing and to transmit a part of the load from said beams to said thrust bearing.

17. In a device of the class described, in combination a track, wheels operating on said track, a pair of substantially parallel channel beams, a runway for a truck formed by the flanges of said beams, a reinforcing member rigidly fixed to each of said beams and forming an additional flange on each of said beams, a centrally placed thrust bearing adapted to carry part of the load on said channel beams and to facilitate rotation, a pair of substantially arched transverse members adapted to receive said centrally placed thrust bearing and to transmit a part of the load from said beams to said thrust bearing and an additional pair of transverse members to fix said beams in a definite position relative to each other.

In testimony whereof, I have signed my name to this specification this fifth day of March, 1921.

H. P. MARTIN.
